H. H. BROWN

AUTOMOBILE JACK

Filed June 23, 1921

Inventor
Harold H. Brown
By his Attorney
Newell & Spencer

UNITED STATES PATENT OFFICE.

HAROLD H. BROWN, OF CENTERPORT, NEW YORK.

AUTOMOBILE JACK.

Application filed June 23, 1921. Serial No. 479,742.

This invention relates to jacks, and more particularly to jacks of a type that are in common use in connection with automobiles.

It frequently happens that in running an automobile, the rear wheels become partially embedded in sand or mud so that it is impossible to extricate the automobile by its own power. When this occurs, a powerful pulling device is needed to extricate the car. To meet this need, special pulling devices have been produced, but these devices are comparatively expensive and occupy a considerable part of the storage space of the car.

The principal object of the present invention is to produce a jack of the general type above referred to, which may be employed in the usual manner to jack up the axle of an automobile, and which also may be conveniently employed as a powerful pulling device to start the car when the rear wheels have become embedded.

With this object in view, the invention comprises the novel and improved features, constructions and combination of parts hereinafter described and particularly pointed out in the claims, the advantages of which will be readily understood and appreciated by those skilled in the art.

The invention will be clearly understood from the accompanying drawings illustrating the invention in its preferred form and the following detailed description of the construction therein shown.

In the drawings, Fig. 1 is a view in front elevation partly in section of a jack embodying the invention;

Fig. 2 is a view in side elevation of the jack;

Figs. 3 and 4 are plan views illustrating the jack in operation; and

Fig. 5 is a detail plan view showing a modified construction of the base plate of the jack.

The invention may be embodied in any convenient form of jack comprising a base or support and a lifting bar or slide mounted to slide longitudinally relatively to said base.

In the form of the invention illustrated in the drawings, the jack comprises a standard 2 mounted on a base plate 3, and a lifting bar or slide 4 mounted to slide longitudinally in the standard 2. The slide 4 is actuated by the rotation of a bevel gear 5 rotatably mounted on the lower end of the

slide and having a threaded engagement therewith. The gear 5 is in mesh with a second bevel gear 6 fixed in the bearings in the standard 2. To the outer end of the shaft 7 is attached a toothed wheel 8 adapted to be engaged by either end of a double-ended pawl 9 pivoted at 10 on an operating lever 11 loosely mounted on the outer end of the shaft 7. The pawl is acted upon by a leaf spring 9 mounted on the lever 11 and arranged to engage a projection on the pawl so as to hold either end thereof in engagement with the toothed wheel 8. The toothed wheel 8 thus may be rotated to actuate the slide 4 by the oscillation of the lever 11. With the proper adjustment of the pawl 9, the toothed wheel may be rotated in either direction to raise or lower the slide 4.

To enable the jack to be employed as a pulling device, a device for the attachment of a connecting member such as a bar, rope or cable, is mounted on the slide 4 preferably at its outer end. Preferably, this device consists of a hook indicated at 14 in the drawings facing in the direction of movement of the slide 4. As shown in the drawings, this hook is passed through one link of a chain 16, which constitutes the connecting member through which the pulling force of the jack is exerted. The base 3 of the jack is extended on the side on which the hook 14 is arranged to support the jack when used as a pulling device and the base is provided with a slot 18 through which the chain may be passed when the jack is in use as a pulling device.

In using the jack as a pulling device, the base of the jack may be engaged with a tree, stake or other abutment, and the hook 14 is inserted in one of the links of the chain 16, as shown in Fig. 3. The other end of the chain is then attached to the axle or any other suitable part of the car. When the jack is connected with the car in this manner and the lever 11 is actuated to project the slide 4 from the standard 2, the car will be pulled along by the action of the jack. If the projection of the slide 4 to the limit of its movement relatively to the standard 2 is not sufficient completely to extricate the car, the slide after one complete projecting movement thereof may be forced back to starting position again, the hook 14 disengaged from the link in the chain 16 and inserted in another link in the chain nearer the car, and the operation repeated.

Instead of holding the standard of the jack stationary by placing the base of the jack against an abutment, provision is also made for attaching the standard to a stake, tree or similar member by means of a cable or chain. In the construction shown, two laterally projecting hooks 18 adapted to be inserted in the links of a chain or in loops in a cable are secured to the sides of the standard. These hooks face in a direction opposite to the direction of the movement of the slide 4.

In using the jack in the manner shown in either Fig. 3 or that shown in Fig. 4, the jack is preferably laid upon the ground and may be held from turning about its point of support by one or more stakes driven into the ground at the sides thereof. Such a stake is indicated at 23 in Fig. 3.

As shown in Fig. 4, the standard of the jack is attached to a stake 20 by means of a chain 22 passed about the stake and having its ends attached to one of the hooks 18 by the insertion of the hook through the links thereof. With the jack thus attached to the stake 20, the jack may be used as a pulling device in the manner hereinbefore described.

When the slide 4 has been projected to the limit of its movement and it is desired to hold the car in position while the slide is being forced back to starting position and the hook 14 is engaged in another link in the chain 16, a pin, bolt or suitable tool may be passed through one of the links in the chain adjacent the base plate and between the same and the hook 14. In order to hold the pin from sliding off the base plate, projections 24 may be formed on the base plate so as to engage the pin as shown in Fig. 1, the pin being illustrated in dot and dash lines in this figure. If a cable or bar is substituted for the chain 16, a suitable clamp may be employed instead of the holding pin to hold the cable or bar in position.

Instead of a slot in the base plate being provided for the passage of the chain 16, the base plate may be formed with a hole through which the chain is passed so that the engagement of that part of the base plate surrounding the chain with the chain will assist in holding the jack in position during the operation thereof.

Fig. 5 of the drawing shows a construction in which the base plate of the jack is formed with a slot indicated at 25, the outer end of which is closed by a roll 26 mounted to rotate on a pin 28 passing through the roll and having its ends engaged in the spaced portions of the base plate. This construction provides an opening in the base plate through which the chain may be passed, and the roll 26 constitutes an anti-friction device for engagement with the chain during the operation of the jack.

The jack not only may be employed in the

manner described as a pulling device to pull the car along, but it also may be employed advantageously as a lifting device to lift the engine out of its bed or to lift other heavy weights. In using the jack as a lifting device, a chain may be thrown over the limb of a tree or other suitable support and its ends attached respectively to the hooks 18 on opposite sides of the standard 2. The chain 16 is then attached to the engine or other object to be lifted.

The construction above described, which enables the jack to be employed as a pulling device, does not interfere in any way with the normal operation of the jack.

It is to be understood that except as defined in the claims, the invention is not limited to the particular construction and arrangement of parts of the illustrated embodiment of the invention, but that the invention may be embodied in other forms within the scope of the claims.

Having explained the nature and object of the invention and having specifically described a device embodying the invention in its preferred form, what is claimed is—

1. A jack adapted for use as a lifting or pulling element, comprising a base, a lateral extension projecting from said base and having a passage therethrough, an abutment adjacent the outer end of said lateral extension, a standard projecting from said base, a bar mounted in said standard and having movement longitudinally thereof, means mounted on said standard for moving said bar, a head carried by the outer end of said bar, a hook carried by said head, said hook adapted to occupy a position in alignment with the passage through the lateral extension of the base, and hooks carried by said standard and diametrically opposed with respect to each other and substantially right angularly disposed with respect to the hook carried by the head, whereby to provide attaching means for an anchoring means for the jack when used as a pulling element without interference with the operation of the bar and its associated hook.

2. A jack adapted for use as a lifting or pulling element, said jack comprising a base, a lateral extension projecting from said base and having a passage therethrough, an abutment adjacent the outer end of said lateral extension, a standard projecting from said base, a bar mounted in said standard and having movement longitudinally thereof, means mounted on said standard for moving said bar, a head carried by the outer end of said bar, a hook carried by said head and providing means for attaching a pulling connection to said bar, said hook adapted to occupy a position in alignment with the passage through the lateral extension of the base when the jack is used as a pulling element, and a plurality of oppositely dis-

posed hooks carried by said standard and arranged in a plane at right angles to the lateral extension of the base and the aforementioned hook carried by the head, said 5 oppositely disposed hooks providing an attachment for means whereby the jack may be anchored when used as a pulling element without interference with the operation of the pulling connection attached to the hook of the head. ¹⁰

Signed at New York city, N. Y., this 17th day of June, 1921.

HAROLD H. BROWN.
